SICKLE GUARD FOR HARVESTERS

Archie E. Neal and James G. Storms, Garfield, Wash.,
assignors to The J. E. Love Company, Garfield, Wash.

Filed Feb. 16, 1971, Ser. No. 115,929

Term of patent 14 years

Int. Cl. D15—03

U.S. Cl. D40—1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 1 is a top plan view of the sickle guard, showing our new design;

FIG. 2 is a bottom plan view;

FIG. 3 is a sectional view taken through line 3-3 in FIG. 1;

FIG. 4 is a sectional view taken through line 4-4 in FIG. 1;

FIG. 5 is a fragmentary sectional view taken through line 5-5 in FIG. 1;

FIG. 6 is a sectional view taken through line 6-6 in FIG. 1;

FIG. 7 is a fragmentary sectional view taken through line 7-7 in FIG. 1;

FIG. 8 is a fragmentary sectional view taken through line 8-8 in FIG. 1;

FIG. 9 is an end view taken from the left in FIG. 1;

FIG. 10 is an end view opposite to FIG. 9;

FIG. 11 is a sectional view through line 11-11 in FIG. 1;

FIG. 12 is a front view of the sickle guard; and

FIG. 13 is a rear view.

We claim:

The ornamental design for a sickle guard for harvesters, as shown.
